UNITED STATES PATENT OFFICE.

BERNARD MORLEY FLETCHER, OF LONDON, ENGLAND.

APPARATUS FOR UTILIZING POWER OF SEA-WAVES.

SPECIFICATION forming part of Letters Patent No. 581,067, dated April 20, 1897.

Application filed June 20, 1896. Serial No. 598,313. No model.)

To all whom it may concern:

Be it known that I, BERNARD MORLEY FLETCHER, a subject of the Queen of England, residing at London, England, have invented certain new and useful Improvements in Apparatus for Utilizing the Power of Sea-Waves, of which the following is a specification.

Various attempts have been made from time to time to obtain useful energy from the vertical oscillation of a buoy caused by the motion of waves, but none of these have hitherto met with conspicuous success. The chief reason for the failure of the previous attempts lay in the difficulty which was experienced in obtaining a fixed point relatively to which the floating buoy was to oscillate vertically, but which should, nevertheless, always remain a constant distance from the middle point of the vertical travel of the buoy, that is to say, from the undisturbed level of the water. A point fixed relatively to the bottom of the sea clearly does not satisfy this condition, as the rise and fall of the general level of the water due to the tides alters the distance of the undisturbed level of the water from the bottom. By my invention I am enabled to overcome this difficulty and provide a purchase-point capable of offering resistance to upward and downward forces and yet which shall always remain an approximately constant distance below the undisturbed level of the water, that is below a horizontal plane intermediate between the crests and troughs of the waves.

In order that my invention may be clearly understood, I proceed to describe the same with reference to the accompanying drawings, Figures 1 and 2 of which represent in elevation, partly broken away, two different forms of my apparatus, in which the energy developed by the oscillation of the buoy is transformed by pumps into a flow of water under pressure. Fig. 3 is a vertical section of portion of the apparatus shown in Fig. 2.

Like letters indicate like parts throughout the drawings.

A represents a mast, which may be made of any suitable material, but preferably is a hollow tubular metal structure, loaded with weights E at its lower end and carrying a

platform or submerged resistance B, of any suitable size or shape. The mast or equivalent provides the flotation-power necessary for the platform. The platform or submerged resistance B serves to steady the mast in the water and keep it submerged to the required depth. If the weight of B is not sufficient for this, the weights E are added. The platform B may be rigidly connected to the mast and secured in a plane perpendicular to the mast by stays B' or other suitable means.

The mast and platform are so weighted that the mast shall float in a vertical position with the platform B immersed to a considerable depth, leaving a convenient length of the mast projecting above the surface of the water. It will be found that such a platform will offer resistance to a vertically-displacing force.

I may employ any desired number of platforms on the mast, and they can be of any suitable size and shape to increase the resisting power, and I may use any convenient number of masts to connect the platforms and provide the necessary purchase for the operation of the buoy or buoys hereinafter to be described.

F represents a buoy or other suitable float of convenient size and shape, which, as shown, consists of a cylindrical air-tight vessel provided with an axial cylindrical aperture F', through which the mast passes. This buoy is designed to rise and fall with the waves, while the mast, owing to the resisting power of the platform B, remains comparatively stationary, and it is from this motion of the buoy that the requisite useful energy is obtained and transmitted by any suitable means.

Any suitable construction of buoy may be adopted, and I may employ two or more buoys suitably connected together.

For the conversion of the motion of the buoy into energy which can be transmitted to a convenient distance I may employ one or more double-acting pumps, directly actuated by the reciprocating buoy to deliver water under pressure to any convenient position for the utilization of the energy so obtained. In Fig. 1 two such pumps are shown, adapted to take in water through the inlets G' at both the up and down stroke and to deliver it un-

der pressure into a common delivery-pipe H, which may be flexible and of sufficient length to reach the place where the energy is required. The pump-barrels G G are carried by the buoy F, and the rods I by a cross-head A', secured on the mast A, but these arrangements may be varied to suit the requirements of each particular case. The delivery-pipe H will deliver the water to any suitable apparatus—an elevated tank or an accumulator, for instance—from which the pressure of the water may be utilized.

In Fig. 2 I have represented the apparatus as provided with only one double-acting pump, of which the barrel G may constitute virtually an extension of the cylinder F. (Shown in Fig. 1.) The plunger or piston G² of this pump is secured on the mast A, which is thereby caused to fulfil the function of a pump-rod and at the same time serve for guiding the buoy F in its upward and downward movement, as before described. The two ends of the barrel G, or the lower end of this barrel and the upper end of the cylinder, are provided with leather or equivalent packing-rings G³, as shown, for example, in Fig. 3, which form proper working joints around the mast A.

In respects other than those last described the apparatus shown in Fig. 2 is substantially similar to that before described with reference to Fig. 1, so that further description thereof is unnecessary.

I consider that in most cases pumps are the best means of converting the motion of the buoy into available energy, but cases may arise where other means would be more suitable, and I wish it to be understood that I do not in any way limit myself to the use of pumps for such purpose.

I may employ any suitable method of mooring my apparatus, and when necessary may attach the cable or chain to any convenient part.

More than one apparatus such as I have described may be made to discharge into a common delivery-pipe or otherwise operate together.

The flow of water under pressure as obtained from my apparatus may be used to drive a hydraulic motor or to perform other useful work.

Having now particularly described and ascertained the nature of my said invention and in what manner the same is to be performed, I declare that what I claim is—

1. The combination of a mast adapted to float in a vertical position with its upper end a suitable height above the water-level, and being of a length to extend into the comparatively undisturbed region of water, means for resisting vertical displacement of the mast, and a float or buoy moving on said mast with the rise and fall of the waves, substantially as described.

2. The combination of a mast adapted to float in a vertical position with its upper end

a suitable height above the water-level, and being of a length to extend into the comparatively undisturbed region of water, a submerged resistance overcoming vertical displacement of the mast, and a float or buoy moving on said mast with the rise and fall of the waves, substantially as described.

3. The combination of a mast adapted to float in a vertical position with its upper end a suitable height above the water-level, and being of a length to extend into the comparatively undisturbed region of water, a submerged resistance overcoming vertical displacement of the mast, and capable of rising and falling with the tide, and a float or buoy moving on said mast with the rise and fall of the waves, substantially as described.

4. The combination of a mast adapted to float in a vertical position with its upper end a suitable height above the water-level, and being of a length to extend into the comparatively undisturbed region of water, means for resisting vertical displacement of the mast, a float or buoy moving on said mast with the rise and fall of the waves, and means for converting the motion of the float or buoy into energy and for transmitting this energy to a distant point for use, substantially as described.

5. The combination of a mast adapted to float in a vertical position with its upper end a suitable height above the water-level, and being of a length to extend into the comparatively undisturbed region of water, a resistance against vertical displacement of the mast, a cylindrical air-tight buoy moving with the rise and fall of the waves and having a central aperture through which the mast passes, and means for converting the motion of the buoy into energy for use at a distant point, substantially as described.

6. The combination of a mast adapted to float in a vertical position with its upper end a suitable height above the water-level, and being of a length to extend into the comparatively undisturbed region of water, means for resisting vertical displacement of the mast, a float or buoy moving on said mast with the rise and fall of the waves, and a pump also moving on the mast and operated by the float, substantially as described.

7. The combination of two flotation-bodies of which one is capable of rising and falling with the waves or agitated surface of the water, and the other body being constituted in part by a resistance which maintains the body in a practically fixed position vertically, the said resistance being submerged at a depth at which the water is comparatively undisturbed, substantially as described.

8. The combination of a hollow mast adapted to float in a vertical position with its upper end a suitable height above the water-level, and being of a length to extend into the comparatively undisturbed region of water, a float moving on the mast with the rise and fall of the waves, and a submerged resistance or

platform for the mast, substantially as described.

9. The combination of a mast adapted to float in a vertical position with its upper end at a suitable height above the water-level, and being of a length to extend into the comparatively undisturbed region of water, a float moving on the mast with the rise and fall of the waves, and a submerged resistance for the mast comprising a platform supported in

position relative to the mast, substantially as described.

In testimony whereof I have hereto set my hand in the presence of the two subscribing witnesses.

BERNARD MORLEY FLETCHER.
